UNITED STATES PATENT OFFICE.

JOHN RUTHERFORD ANDERSON, OF MACON, GEORGIA.

HORSESHOE.

SPECIFICATION forming part of Letters Patent No. 511,489, dated December 26, 1893.

Application filed October 28, 1893. Serial No. 489,350. (No model.)

To all whom it may concern:

Be it known that I, JOHN RUTHERFORD ANDERSON, a citizen of the United States, residing at Macon, in the county of Bibb and State 5 of Georgia, have invented certain new and useful Improvements in Horseshoes; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

My invention relates to an improvement in 15 that class of horse shoes which are designed to prevent the horse from slipping on smooth pavements, ice and other slippery surfaces, and my principal object is to provide a device which will give the horse a firmer hold 20 on the ground than any heretofore known.

A further object is to provide an arrangement which will serve to cushion the horse's hoof when stamped down on the ground and thus prevent the various diseases occurring 25 from the concussion occasioned from such blows.

To these ends the invention consists of a shoe having formed on its wearing surface a series of substantially semi-spiral ribs or flut- 30 ings extending diagonally across the shoe and in opposite directions on each arm thereof.

Referring to the accompanying drawings which represent my invention: Figure 1 represents a bottom plan; Fig. 2 a diagonal section on line II—II; and Fig. 3 a longitudinal section on line I—I.

The reference letter *a* indicates the shoe proper which is shown in the drawings as bottom upward, and it has formed on such bottom the ribs *b*, which begin at or near the extremities of the arms and extend from the inner edge forward toward the toe of the shoe and outward at an angle of about forty-five degrees and each rib is formed in the shape 45 of a double curve, beginning at the inner edge of the arm and making one turn at *e*, and the other at *f*, each turn being adjacent to the inner and outer edges of the arms, respectively, thereby giving the bottom of the 50 arm of each shoe the appearance of one half of an open spiral or coil. These ribs extend parallel with each other from the extremities of the arm to the toe of the shoe, and at this latter point the two ribs meet and by this meeting

a V-shaped appearance is given to the shoe at 55 the toe or point *c*. The space occurring between each of the ribs *c*, is curved gradually downward and thence upward from one rib to another, thus forming a gentle and regular arc between each rib. The function of 60 this peculiar construction is two-fold. First by the diagonal arrangement of the ribs *b*, the shoe is given a firm hold on the earth and as it is impossible for the ribs to be disengaged without pushing apart the arms of the 65 shoe its hold is insured. Further, when the shoe is stamped down on the ground the sharp ends of the ribs will enter the ground but as the inclined sides engage the same the resistance gradually increases until the entire 70 force of the blow is broken. Thus it will be seen that each of the several ribs constitutes a wedge which enters the ground gradually, as distinguished from a flat surface, which engages the ground in a sharp and abrupt 75 manner. The dirt accumulated by the repeated blows of the shoe pressing it in between the ribs serves to prolong the life of the shoe by taking off portions of the strain from the ribs as they come in contact with 80 the ground.

The shoe may be secured to the horse's foot by any preferred means, the usual nails being, however, deemed the best.

In the drawings nail holes are indicated by 85 the letter *d*, and such holes are located in the depressions between the ribs.

Having thus described my invention, what I claim as new, and desire to secure by Letters Patent, is—

A horse shoe having its under or wearing surface formed with a series of integral ribs beginning on each arm at the inner edgethereof, and extending forwardly and outwardly until the outer edge of the arm is reached, 95 each rib being parallel with the one directly adjacent and formed with a double curve *e* and *f*, and with a space, between each rib and the next, sloping downwardly and away from the tops of such ribs, substantially as described.

In testimony whereof I affix my signature in presence of two witnesses.

JOHN RUTHERFORD ANDERSON.
